UNITED STATES PATENT OFFICE.

LEOPOLD DEMUTH, OF NEW YORK, N. Y.

DESIGN FOR A MOUTHPIECE FOR TOBACCO-PIPES.

41,834.

Specification for Design.

Patented Oct. 10, 1911.

Application filed November 18, 1910. Serial No. 593,124. Term of patent 7 years.

To all whom it may concern:

Be it known that I, LEOPOLD DEMUTH, a citizen of the United States, residing at New York, in the county and State of New York, have invented a new, original, and ornamental Design for a Mouthpiece for Tobacco-Pipes, of which the following is a specification, reference being had to the accompanying drawing, forming part thereof, in which—

Figure 1 represents a plan view of a

mouth piece embodying this design. Fig. 2 is a side view thereof. Fig. 3, is an end view of Fig. 1.

I claim:

The ornamental design for a mouth piece for tobacco pipes, as shown.

LEOPOLD DEMUTH.
